UNITED STATES PATENT OFFICE.

ELDRIDGE PACKHAM, JR., OF BALTIMORE, MARYLAND.

DESIGN FOR A BOTTLE.

SPECIFICATION forming part of Design No. 29,171, dated August 9, 1898.

Application filed April 20, 1898. Serial No. 678,312. Term of patent 3½ years.

To all whom it may concern:

Be it known that I, ELDRIDGE PACKHAM, Jr., a citizen of the United States, residing at Baltimore, in the State of Maryland, have invented and produced a new and original Design for a Bottle, of which the following is a specification.

Figure 1 is an elevation or front view of a bottle, showing my new design. Fig. 2 is a central vertical section of same.

The design consists of a circular body the back A of which is a plain convex circular surface embracing the entire area within the circular rim b, and the front has a bold ring-shaped border-molding c adjoining the said

circular rim b, and a depressed convex panel A' is within the said border-molding. The convex back A and the ring-shaped border-molding c at the front unite at the rim b.

Having described my invention, what I claim as new, and desire to secure by Letters Patent, is—

The design for a bottle, as herein shown and described.

In testimony whereof I affix my signature in the presence of two witnesses.

ELDRIDGE PACKHAM, JR.

Witnesses:

CHARLES B. MANN, Jr.,
CHAPIN A. FERGUSON.
